UNITED STATES PATENT OFFICE.

JOHN MORELLO, OF SALT LAKE CITY, UTAH, ASSIGNOR OF ONE-HALF TO FRANK SCAGLIONE, OF SALT LAKE CITY, UTAH.

RAIL JOINER.

Application filed October 4, 1926. Serial No. 139,279.

My invention relates to railroads and has for its object to provide a new and efficient combination of an angle bar, rail plate and joiner. 5
5 A further object is to provide a new and economically constructed angle bar and joiner which will prevent creeping of the rails and which will brace the rails when used on curves. 10
10 A still further object is to prevent rails from splitting, breaking or being turned over. 15
15 A still further object is to provide a joiner which will make a true joint where two rails are joined together and which may be used with or without the usual bolts or if the bolts should become loosened or lost the rails will be held in perfect alinement without danger to the passing trains. 20
20 These objects I accomplish with the device illustrated in the accompanying drawings in which similar numerals of reference indicate like parts throughout the several views and as described in the specification 25 forming a part of this application and as pointed out in the appended claim. 30
30 In the drawings of which I have shown the best and most preferred manner of building my invention, Figure 1 is a side elevation of my device joining two rails together. Figure 2 is an end elevation of my device with the rails shown in place therein. Figure 3 is an end view of the removable locking portion of my device. Figure 4 is a plan view of the same inverted, and Figure 5 is a plan view of the angle bar and rail plate combined. 35
35 In the drawings I have shown the common rail as A and in fastening abutting rails together some form of angle bars has always been used, and on most railway tracks, tie or rail plates are used on each tie, and some use rail plates which are integral or secured to the angle bars and rest on but one tie; therefore, when the train passes over the end of joined rails the end of the rail gives and is forced downwardly and the wheel of the cars strikes the ends of the abutting rail and causes them to creep. Also when the trains are rounding curves the force of the wheels with its combined momentum and weight will cause the rails to turn over sideways unless braced from the outside of the plate. With my device these objections are all eliminated and the rails will be held solid, 55 both from end motion and side movement. The present invention consists of a horizontally disposed base plate B, having one side 1 built upwardly in the shape of the outside of the rail A and to fit under the head of the rail. The opposite edge of the said rail plate is formed upwardly to make a recess 2 under a flange 3. Brace reinforcements 4 are provided back of the side 1 bracing the side from being bent or broken from side 65 pressure from the rail or the load thereon. A hole 6 is provided in the bottom of the plate B with its side walls at an angle to the main plane of the base B. Lugs or bosses 7 are provided on the bottom of the said 70 plate B which are driven into the ties and prevent creeping or side motion of the base. A locking member C is then provided with one edge 5 adapted to fit under the said 75 flange 3 in the recess 2 of the base B. The other edge of the said member is built up and has a flange 8 formed thereon which, when assembled, fits against the inner side of the web of the rail and under the head. Medially on the bottom of the said member C I provide a boss or lug 9, which is shaped similar to the hole 6 and when the device is assembled is adapted to fit within the said hole 6. Holes 10 are provided in both 80 the base and the locking member through 85 which the spikes may be driven when they are secured to the ties. Holes may be bored through the rails and the flanges 1 and 8 through which bolts 11 are passed and secured when the device is assembled. 90
90 To assemble my invention, the base plate B is secured to the ties by spikes and the rails placed under the side 1. The locking member C is then placed in the position with the edge 5 engaging the under side of the 95 flange 3 in the recess 2, with the lug 9 started into the hole 6 of the base plate B. Pressure either by leverage or a blow will force the flange 8 inwardly and downwardly under the head of the rail. As it passes the most projecting point of the head of the rail it will slip freely into position, inwardly until the flange 8 rests against the web of the rail and the lug 9 is engaged in the hole 6. Spikes 100 may then be driven through the holes 10' and the rail is ready for use. 105
105 The device may be made long enough to engage two ties with its lower face resting

on the upper faces of the ties or may be made longer to rest on three or four ties if so desired.

Having thus described my invention I desire to secure by Letters Patent and claim:—

In a rail joiner the combination of a base member having a vertically disposed rail engaging portion formed on one side thereof; a flange formed on the other side; a

locking member adapted to be placed under 10 the flange on said base; a hole through said base and a lug on said locking member adapted to be placed in said hole in the base when said base and locking member are holding a rail.

In testimony whereof I have affixed my signature.

JOHN MORELLO.
